GAME DEVICE

Albert H. Hardman, 1220 Cochran Road, Pittsburgh, Pa.

Filed Sept. 30, 1959, Ser. No. 57,737

Term of patent 14 years

(Cl. D34—15)

The single figure is a perspective view of the game device showing my new design.

The side wall not shown is substantially the same as that shown, and the rear wall is plain.

The dominant feature of my design resides in the portion shown in full lines. The broken lines showing of a ball is for illustrative purposes only.

I claim:

The ornamental design for a game device, as shown and described.
